UNITED STATES PATENT OFFICE.

PAUL DAIMLER, OF CANNSTATT, GERMANY.

ARMORED AERIAL MACHINE.

1,095,711.

Specification of Letters Patent.

Patented May 5, 1914.

Application filed August 16, 1913. Serial No. 785,084.

To all whom it may concern:

Be it known that I, PAUL DAIMLER, subject of the King of Wurttemberg, residing at 87 Waiblingerstrasse, Cannstatt, Kingdom of Wurttemberg, Germany, have invented certain new and useful Improvements in Armored Aerial Machines, of which the following is a specification.

This invention relates to propeller-driven armored aerial machines and is applicable to screw-propelled aerial machines of all types whether aerostats or aeroplanes.

The object of the present invention is to enable aim to be taken in the direction of the propeller shaft without hindrance from the propeller.

According to the present invention the propeller shaft is constructed, in a manner hitherto known, as a countershaft driven from the motor crank shaft and is made hollow to receive a gun of any suitable type so that the gun may be discharged through the propeller shaft without hindrance from the propeller. The propeller shaft is preferably of sufficiently large internal diameter to enable the barrel of the gun to be adjusted therein at an angle to the axis of the shaft in order to enable the gun to be directed at a suitable angle.

In order that the invention may be more clearly understood, reference is made to the accompanying drawing which illustrates by way of example one embodiment of my invention, the figure being a fragmentary side view of an aerial machine, parts being shown in section.

The engine cylinders *a* are arranged in a manner hitherto known in an inverted position on the framework of the aerial machine so that the motor shaft *b* lies above the cylinders *a*. The propeller shaft *c* is arranged above the motor shaft *b* and driven therefrom through gearing *d* and *f*. The propeller shaft *c* is made hollow to receive the barrel *g* of any suitable type of gun, the breech *h* of the gun being arranged behind the rear bearing *e* of the propeller shaft. The gun may be of any suitable type such as, for example, a machine gun, the essential feature being that the gun is so arranged that the projectile is discharged through the hollow propeller shaft *c*. It will of course be understood that the pro-

peller and its hollow shaft *c* may be arranged either at the front or rear of the aerial machine.

On the drawing, the hollow propeller shaft *c* is shown of greater internal diameter than the external diameter of the gun barrel *g*, thereby permitting the gun barrel to be tilted within the propeller shaft for sighting purposes.

I claim:

1. In a propeller-driven armored aerial machine, means for enabling gun firing in the direction of flight comprising, in combination, a hollow propeller shaft carrying the propeller and a gun in line with said shaft and adapted to discharge therethrough.

2. In a propeller-driven armored, aerial machine, means for enabling gun firing in the direction of flight comprising, in combination, a hollow propeller shaft carrying the propeller and a gun having its barrel located in said shaft.

3. In a propeller-driven armored aerial machine, means for enabling gun firing in the direction of flight comprising, in combination, a hollow propeller shaft carrying the propeller and a gun having its barrel located normally in line with but capable of adjustment at an angle to the axis of the shaft.

4. In a propeller-driven armored aerial machine, in combination, a motor having its cylinders inverted, a crank-shaft above and driven by said motor, a hollow propeller shaft mounted above and driven from said crank-shaft and a gun in line with said propeller shaft and adapted to discharge therethrough.

5. In a propeller-driven armored aerial machine, in combination, a motor having its cylinders inverted, a crank-shaft above and driven by said motor, a hollow propeller shaft mounted above and driven from said crank-shaft and a gun having its barrel located in said propeller shaft.

6. In a propeller-driven armored aerial machine, in combination, a motor having its cylinders inverted, a crank-shaft above and driven by said motor, a hollow propeller shaft carrying the propeller and mounted above and driven from said crank-shaft and a gun having its barrel normally in line

with but adjustable at an angle to the axis of said propeller shaft.

7. In a propeller-driven aerial machine, a motor, a crank-shaft driven by said motor, 5 a hollow propeller shaft driven from said crank-shaft and a gun having its barrel located in said propeller shaft, the latter being of greater internal diameter than the external diameter of the gun barrel to per-

mit the latter to be tilted within said propeller shaft.

In testimony whereof I have affixed my signature in presence of two witnesses.

PAUL DAIMLER.
